UNITED STATES PATENT OFFICE.

JAMES MARSDEN, OF WIGAN, ENGLAND.

DESIGN FOR A PATTERN-CHART.

SPECIFICATION forming part of Design No. 29,599, dated November 1, 1898.

Application filed September 21, 1898. Serial No. 691,564. Term of patent 14 years.

To all whom it may concern:

Be it known that I, JAMES MARSDEN, a subject of the Queen of Great Britain, residing in Wigan, in the county of Lancaster, England, have invented and produced a new and original Design for a Pattern-Chart, of which the following is a specification, reference being had to the accompanying drawing, forming a part thereof.

10 The drawing is a plan view of the pattern-chart, showing my new design.

As shown in the drawing, the leading or material feature of my design consists of a new arrangement of patterns for pieces or sections 15 of corsets. A number of sets of double-gore-shaped pieces are arranged longitudinally upon the pattern - chart, the double - gore-

shaped pieces of the different sets being marked 0, 1, 2, 3, 4, 5, 6, and 7. All of the parts having the same reference belong to 20 the same set for making a complete corset.

Having thus described my invention, what I claim as new, and desire to secure by Design Letters Patent, is—

25 The design for a pattern-chart substantially as shown and described.

In witness whereof I have hereunto signed my name, this 5th day of September, 1898, in the presence of two subscribing witnesses.

JAMES MARSDEN.
